UNITED STATES PATENT OFFICE.

ALFRED G. F. KUROWSKI, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed July 14, 1925. Serial No. 43,492.

This invention relates to stencil-card-holding-and-typing devices for typewriting machines, in which a card-holding frame is arranged to reciprocate tangentially to a rev-
5 oluble platen.

This device is particularly arranged for use in connection with stencil-cards for addressing machines which comprise a comparatively heavy paper or cardboard frame
10 having an opening, across which is stretched a stencil-sheet. It is sometimes desirable to type some information on the paper-frame, and then withdraw or silence the typing ribbon to write the full name and address
15 on the stencil-sheet directly with the bare types.

There is disclosed improved means for automatically controlling the ribbon mechanism, so that it may be vibrated in front of
20 the types at certain times, but silenced while the types are striking the stencil-blank.

According to certain features of this invention, the stencil-card is placed in a card-holding frame, tangentially disposed in
25 front of the platen, and, by means of a handle the card-holding frame, is lowered to a point to receive the first line of typing at the upper edge of the paper-frame. Novel mechanism is effective at this position of the
30 card to vibrate the ribbon, and consequently a line is typed upon the frame of the card. By means of the usual line-spacing mechanism, the card may be line-spaced several lines during the typing of other lines upon
35 the card-frame, with the aid of the ribbon.

The card-controlling handle is then swung, and by means of a novel stop-device the handle is arrested in a position corresponding to the first line of typing upon the
40 stencil-sheet. During the swinging of the handle to raise the card, the ribbon-vibrating mechanism is silenced, and automatically the machine is converted into a stencil-cutter. By means of the line-spacing
45 mechanism, the card may again be line-spaced in the regular way as fresh lines of typing are cut into the stencil-sheet.

In order to permit the line-spacing of the card while cutting into the stencil-sheet, the
50 stop-device, designed to arrest the handle in a position corresponding to the first line of typing on the stencil-sheet, is automatically withdrawn as the handle is released, thereby making it possible to move the

handle further to the rear as the card is 55 line-spaced.

From the foregoing, it will be seen that the card is handled with a minimum effort on the part of the operative, who need not shift the ribbon-mechanism, which is automatically thrown into operation when needed and silenced when not required.

Owing to the comparatively long cards used in this type of machine, and to the desirability of presenting the card to the 65 platen in a flat condition, it is contrived to lower the card in an inclined path tangential to the platen. This clears the type-bar segment, which is placed below the platen and in line therewith. The printing point is, 70 in this invention, considerably below the plane of the platen-axis, as usual heretofore. To vibrate the ribbon in front of the inclined card, in a path parallel thereto, novel mechanism is provided.

In order to eliminate the blurring of the typing, which would occur if the type-bar-heads were caused to bear upon the work-sheet, and also to improve the return speed of the type-bars, there is usually provided 80 an anvil against which the type-bars strike previously to striking the work-sheet, the printing upon the sheet being caused by the resiliency of the type-bars. In order that this feature may be maintained both while 85 typing upon the stencil-frame and upon the stencil-sheet, novel mechanism is provided whereby the anvil may be adjusted slightly towards and away from the platen. The difference in thickness between the card-frame and the stencil-sheet is automatically 90 compensated for by the position of the card-frame.

When cutting the stencil-sheet, it is desirable to provide a backing for the card to 95 both protect the types and facilitate the cutting of the stencil-sheet. Novel means are provided to automatically present the backing to the stencil-sheet only, the platen being rotated while line-spacing the card. In this 100 manner, owing to the positive gear connection between the platen and the card-frame, and, due to the standardization of the cards, the stencil-sheet therein at all times corresponds to the same portion of the platen, 105 which is covered with a celluloid strip fastened to the platen by means of a clamping member, so built into the platen as to pre-

sent an unobstructed platen-surface, and thus permit the feeding of the cards up and down as the platen is rotated in a path tangential thereto. In order to facilitate the reading of the typed matter upon the stencil-sheet, there may be provided inking means wrapped around the celluloid strip and fastened to the platen with the celluloid by means of the same holding device.

10 Other features and advantages will hereinafter appear.

In the accompanying drawings,

Figure 1 is a cross-sectional view, in elevation, through the center of an Underwood standard typewriting machine having the invention applied thereto, the card being shown in its uppermost or inserting position.

Figure 2 is a detail, showing a portion of the ribbon-vibrating mechanism.

20 Figure 3 is a detail, showing the connection between the ribbon-vibrator-controlling shaft, and the compensating anvil for arresting the blows of the type-bars.

Figure 4 is a cross-sectional view, in elevation, through the center of the machine, showing the card in its lowermost position for receiving the first line of typing thereon, the ribbon-vibrating mechanism being thrown in its effective position.

30 Figure 5 is a cross-sectional view through the line 5—5 of Figure 4.

Figure 6 is a fragmentary cross-sectional view, in elevation, through the center of the machine, showing the type-bar and the ribbon-vibrator in their operated positions.

Figure 7 is a cross-sectional view, showing the construction of the card-positioning handle.

40 Figure 8 is a perspective view of the ribbon-vibrating-mechanism-controlling shaft and of a locking device therefor.

Figure 9 is a cross-sectional view, in elevation, through the center of the machine, showing the card in a position for receiving the first line of typing upon the stencil-sheet.

50 Figures 10, 11 and 12 show different positions of the platen, which are required to readily replace the celluloid backing covering a portion of the periphery of the platen.

Figure 13 is a fragmentary cross-sectional view of the platen, showing the inking means provided to render visible the typing on the stencil-sheet.

55 Figure 14 is a perspective view, showing one of the side frames of the stencil-unit.

Figure 15 is a perspective view of the stopping plates controlling the positions of the card.

60 Figure 16 is a plan view of the stencil-device, as applied to an Underwood standard typewriting machine, the carriage thereof being shown at line-starting position.

65 Figure 17 is a fragmentary view, in cross-section, showing the anvil-holding means.

Figure 18 is a front view, in elevation, showing the anvil-controlling mechanism.

Figure 19 is a fragmentary longitudinal sectional view, partly in elevation, through the line 19—19 of Figure 12.

70 Figures 20 and 21 show the card-holding frame, respectively, arranged for a thick and a thin card.

Figures 22, 23 and 24 are respectively a cross-sectional view, a front view and a fragmentary side view, of a modified and simplified form of ribbon-controlling mechanism.

75 Figure 25 is a front view of the card, showing lines of typing upon both the frame and the stencil-sheet.

Figures 26 and 27 are different views of a modified form of the card-positioning-handle-stop-device; said stop-device being shown respectively in its ineffective and effective positions.

Figure 28 is a perspective view of a modified form of the stop-device for controlling the position of the card.

This invention is illustrated as applied to an Underwood standard typewriting machine and is particularly suited for the handling of cards, such as used in some addressing machines. In Figure 25 there is shown a stencil-card 10 consisting of a heavy paper or cardboard frame having an appendage at the top thereof, upon which it is desired to type several lines 11 for the purpose of identifying, or otherwise relating to the addresses typed upon a stencil-sheet 12, stretched across an opening 13 in the lower part of the card, the typing 14 on the stencil-sheet being, of course, desirable to be typed with the bare type, so as to cut into the sheet, thus providing a passage for the ink.

100 According to the method of handling the card 10, the same is inserted in a recess 15 in side frames 16, behind plates 17, and is lowered all the way down against a stop-bar 18, which forms an integral part of the side frames 16 comprising the card-holding frame. The position of the card after being inserted in the card-holding frame is illustrated in Figure 1.

110 The card-holding frame is then lowered to the position shown in Figure 4, for the purpose of writing the first line of typing at the top of the card. In order to quickly and positively lower the card to printing position, there is provided novel mechanism including a handle 19 operatively connected to a sector 20 geared at 21, and engaging with a pinion 22. The pinion 22 is fast to a platen-shaft 23, which carries, fast thereto, a platen 24 and a pair of gears 25, in turn meshing with racks 26, forming an integral part of the card-holding frame. In view of the disclosed mechanism, it is obvious that, upon swinging the handle for

wardly, the sector will also be swung, and consequently the card will be lowered.

As it is one of the main features of this invention that the ribbon-vibrating mechanism shall be automatically controlled by the movement of the card in a manner to afford the rising of the ribbon in front of the types at each key-depression, there is provided mechanism which is operatively connected to a universal bar 27. In order to more fully comprehend the operation of the ribbon-vibrating mechanism, first the action of the type-bars will be described.

Upon depressing each key (not shown), a key-lever 28 is swung on a fulcrum-shaft 29 against the action of a spring 30, and, by means of a pin 31 engaging with a slot in an intermediate lever 32, the latter is also swung on a pivot 33. The lever 32 is provided 20 at the upper end thereof with a pin 34 engaging a slot in a type-bar 35, whereupon, upon depressing the key, the type-bar is swung on a supporting pin 36, thus striking the card by means of a type 37. In order to letter-space the carriage after each type-impression, there is provided mechanism comprising a pair of dogs 38, engaging with an escapement-wheel 39, which, in turn, engages, by means of a pinion 40 and a rack 41, with the carriage. The dogs 38 are controlled by the universal bar 27 which is bent downwardly at 42 and then rearwardly at 43, and again upwardly at 44, forming a pocket 45 for the card. The universal bar 30 is supported in the regular manner upon a supporting member 46 sliding in the type-bar segment 47 and upon a rocking arm 48 at the rear of the machine. It will be understood that upon swinging each type-bar, the 40 universal bar is moved to the rear, because each type-bar is provided with a heel 50 striking a curvate sector 51, which forms an integral part of said universal bar, which is operatively connected to the escapement-dogs 45 at 52.

Normally, in a typewriting machine, the universal bar is operated back and forth at each key-depression. In the present machine, a ribbon 53 is held silent in its normal 50 position below the printing point, as shown in Figure 1. However, upon lowering the card-holding frame and immediately after the stencil-sheet passes the printing field, the ribbon is operatively connected to a round pin 54 fast to a bracket 55, forming a part of the universal bar. Novel mechanism is provided in this invention for the purpose of connecting the ribbon-mechanism to the universal bar when the paper-frame of the 60 card is in the printing field, and for silencing the ribbon while the stencil-sheet is in the printing field. As it is proposed to switch the ribbon-mechanism automatically, mechanism is also provided which, in one 65 form of this invention, comprises a cross-bar

56 fast to the stop-bar 18 of the card-holding frame, and a rotatably mounted plate 58 having two teeth 59 and 60 engaging with the bar 56. As the frame is lowered, the bar 56 strikes the lower tooth 60, and the 70 plate 58 is rotated to the position shown in Figure 4, whereupon a link 61, operatively connected to said plate 58 at 62, is drawn up, thus rocking an arm 63 to which the link 61 is connected at 64. The arm 63 is fast to a 75 shaft 65 rotatably mounted in a bushing 66 fast to a supporting bracket 67. At the other side of the bushing 66, the shaft is provided with a head 68 forming an integral part thereof, into which head a shoulder-stud 80 69 is screwed eccentrically with the shaft, and upon which screw a ribbon-controlling arm 70 is rotatably mounted. Said arm 70 is fast to a bushing 71, which carries at the other side thereof, also fast thereto, an upwardly-extending arm 72, having an open slot 73 at the end thereof, designed to engage the pin 54 in the universal bar. According to this arrangement, the arm 70 forms substantially 85 an integral part of the arm 72, so that, when the latter is engaged with the pin, and the universal bar is moved, then both arms are rocked on their supporting stud 69, thereby lifting the ribbon in front of the types by means of a link 74 operatively connected to 90 the arm 70 at 75. In order that the slot 73 in the arm 72 may be in a position to engage the pin 54 when urged upwardly by the link 61, the arm 70 is provided with a locating finger 76 at the end thereof, normally resting on a rib 77 of the machine-frame, which is generally indicated by the numeral 78. When the arm 72 is raised, the pin 54, while entering the slot 73, acts as a cam and swings 95 the arms 70 and 72 slightly counterclockwise 100 and raises the finger 76 a short distance from the rib 77, as shown in Figure 4.

Owing to the design of the card-holder which is caused to be moved up and down in an inclined path in front of the platen, it is 110 necessary to vibrate the ribbon in front of the card also in an inclined path parallel thereto. To this end, there is provided mechanism which comprises a guiding member 79 fast to the type-bar segment 47 by means of screws 80, and a ribbon-vibrator 81 provided with fingers 82 to guide the ribbon. The ribbon-vibrator is operatively connected to the link 74 at 83, the lower end 115 of the link being connected to the arm 70 120 and allied mechanism in the manner hereinbefore disclosed.

Mechanism is provided to positively hold the ribbon in either its effective or ineffective position, and, in one form of the invention, 125 said mechanism may comprise a roller 84 mounted upon an arm 85 rockably mounted on a fixed stud 86. The roller is designed to co-operate with a tooth 87 on the plate 58, and, owing to the resiliency of the arm

85 actuated by a spring 88, when the plate 58 is rotated by the action of the bar 56, it will be held in place by the force of the roller actuating upon either side of the tooth 5 87. However, such mechanism would require the spring 88 to be comparatively strong, thereby rendering the operation of the handle hard, or else the mechanism would be unreliable. In order to render the 10 timing of the ribbon-mechanism more positive, there is provided a locking member 89, rockably mounted on a shaft 90 journaled in the bracket 67. Said locking member is provided with a tooth 91, engaging with 15 notches 92 by means of a spring 89 in a disk 93 fast to a shaft 94. Referring to Figure 9, it will be noted that the locking member is controlled by a cam-finger 95 fast on the shaft 94 against which finger the bar 20 56 actuates to swing the locking member, thus withdrawing the tooth 91 from engagement with the notches 92 previously to striking either of the teeth 59 or 60, to rotate the plate 58 and to render the ribbon effective to vibrate. 25

Having written one or more lines of typing upon the paper-frame of the card, the handle 19 is then swung to the rear to move the card upwardly in a position to receive 30 the first line of typing upon the stencil-sheet. In order to quickly position the card, and at the same time permit its being line-spaced by means of the line-spacing mechanism 96, the handle is rotatably mounted 35 upon a stud 97, fast to one of the side plates 98, and is provided with a pawl 99 pivotally mounted on a stud 100 fast to the handle so that the rear rim portion of the pawl may engage the sector 20 upon movement 40 of the handle clockwise. Due to the peculiar manner in which the handle is connected to the sector 20, the same may be rotated counterclockwise a small amount before a tab 101, forming an integral part of 45 the handle, strikes the sector, thereby driving the sector therewith. In order to bring the tab 101 in contact with the sector, however, the tension of a spring 102 normally tending to separate the tab from the sector 50 must be overcome, and, in so doing, the pawl 99, which is normally held in the position shown in Figure 4 by the sector bearing upon a heel 103 of the pawl, is permitted to swing to the position shown in Figure 9, in which position it is held by the action of 55 a spring 104, thereby striking a tab 105 of a stop-device 106, the tab extending through an opening 107 in one of the plates 98, thus arresting the swing of the handle and of 60 the card. Upon releasing the handle, the spring 102 is allowed to retract, thereby swinging the handle rearwardly to separate the tab 101 from the sector, and consequently forcing the swinging of the pawl 99 to 65 its normal position, thereby clearing the tab

105 of the stop-device, and consequently permitting the line-feeding of the platen by means of the line-spacing mechanism. In order to accurately position the stencil-card 70 to receive the first line of typing upon the stencil-sheet, the stop-device 106 is rockably mounted upon the stud 97 by means of a screw 108, and is settable upon the plate after being adjusted by means of screws 109 through circular slots 110 in the stop-device 75 106. It will be noted that there is provided a similar stop-device 111 having a tab 112 for the purpose of interposing the sector 20 at 113, as shown in Figure 4, thereby locating the card for its lowermost position. The tab 112 protrudes through an opening 114, which is adjustably mounted on the screw 108 and is settable by means of screws 115 through a circular slot 116. 80

It will be understood that, upon raising the card-holding frame from its lowermost position to a position to receive typing upon the stencil-sheet, the bar 56 strikes the tooth 59 of the plate 58, thereby disconnecting the ribbon-vibrator from its operating pin 54 85 in the universal bar, thus permitting the typing of one or more lines upon the stencil-sheet with the bare type. 90

Owing to the positive gearing, connecting the card-holding frame with the platen, a certain portion of the periphery of the platen corresponds with the opening in the card across which the stencil-sheet is stretched. This condition is taken advantage of, in this invention, to provide a celluloid strip 117 for the types fixed upon a portion of the platen 24 and wrapped therewith. Novel means are provided for holding the strip, and, if desired, an inking medium associated therewith. The holding means may comprise a longitudinal groove 118 cut into the platen, into which groove a bent edge 119 of the strip is placed, as shown in Figure 10. Then the platen is rotated to expose the other bent edge 120 of the strip, as shown in Figure 11, whereupon the edge 120 is forced into a groove 122 behind an eccentric bar 121, which is subsequently rotated to the position shown in Figure 12, thereby binding the edge against 115 the side of the groove 122. Mechanism is provided to rotate the eccentric bar 121, which comprises an operating plate 123 fulcrumed in the platen-axle 23, and operated therearound by means of a finger-piece 125. 120 The plate is provided with a pin 126, engaging with a slot in an arm 127, fast to the bar 121 at the end thereof. 125

In order to compensate for the difference in thickness between the card-frame and the stencil-sheet, there is provided mechanism automatically controlled by the shaft 94, which is, in turn, controlled by the position of the card. It is well known that the Underwood typewriting machine is pro- 130

vided with an anvil against which all the type-bars strike previously to striking the work-sheet, which is struck because of the resiliency of the type-bars. The amount that the type-bars are caused to bend in order to strike the sheet is so small that if the bars were adjusted by the thick cardboard frame of the cards, then the type-bars would not strike the stencil-sheet. In order to eliminate this condition, an anvil 128 is provided adjustably mounted on the type-bar segment in a manner to afford its being built up when typing upon the card, and decreased when typing upon the stencil-sheet. For the purpose specified, a stop-ring or pad 129 is partly milled off in an angle with a vertical plane through the axis of the platen, and the anvil 128 is slidably mounted thereon. The anvil is also milled in an angle, but opposite to the milled angular face of the pad 129, in such a manner that the outer face of the anvil will be substantially parallel to the axis of the platen. It is obvious that by sliding the anvil upon the pad the outer surface will be moved either forwardly or rearwardly depending in the direction the anvil is swung upon its supporting pad, against which it is held by means of studs 130 fast to the anvil as shown at 131 in Figure 17. The studs extend outwardly through slots 132 in the type-bar segment and are provided with a spring 133 held in place by a collar 134 fast to the studs, the spring actuating upon the segment through a washer 135, thus holding the anvil in contact with the supporting pad. The segment is automatically swung in a path determined by the curvature of the slots 132 to positions corresponding to the position of the card, thereby compensating for the different thicknesses thereof, and, to this end, there is provided a lever 136 fulcrumed at 137 upon a fixed bracket 138, one end of the lever being provided with a fork 139 designed to engage a pin 140 fast to the anvil 128. At the other end, the lever 136 is provided with a pin 141 through which the lever 136 is rocked to change the position of the anvil. Said pin 141 is operated by a link 142 which is in turn operatively connected to the shaft 94 through an arm 143 fast thereto and a pin 144 fast to the arm and engaging the lower end of the link 142. Sometimes it is desirable to use cards having a comparatively thin paper-frame, such as is illustrated in Figure 21. In such cases, a suitable card-holding frame may be substituted and the compensating mechanism be not used because the difference in thickness between the paper-frame and the stencil-sheet is so small that it need not be considered, the resiliency of the type-bars being enough to take care of the difference. In one form of the invention, as illus-

trated in Figures 22, 23 and 24, novel means are shown for switching and locking the ribbon mechanism. Instead of the switching and locking means described at the beginning of this specification, the mechanism 70 comprises a Geneva lock, that is to say, a plate 145 having a notch 146 engaging with a tooth 147 on the card-holding frame. Upon moving the card-holding frame the tooth 147 will be caused to engage with the 75 notch 146, thereby swinging a shaft 148, upon which the plate 145 is secured, from a position shown in Figure 22 to that shown in Figure 23. Said plate 145 is provided with two flat portions 149 against which 80 the side of the card-holding frame slides, thereby preventing the shaft from swinging to its original position unless it is urged by the tooth 147. In order to relieve the plate 145 of the weight of the ribbon-85 mechanism which may tend, under certain conditions, to bind and to interfere with the free operation of the card-holding frame, there may be provided an arm-and-roller arrangement 150 engaging with a 90 tooth 151 in a plate 58^a which is fixed relatively to the carriage. The shaft 148 is rotatably mounted on the plates 98 and moves therewith, being positioned thereon by means of a nut 152 and a washer 153. 95 The plate 145 is fast to the shaft 148 in order to have it, at all times, in engagement with the tooth 147, but the plate 145, being operatively connected to the ribbon-mechanism which is stationary, must also be stationary. To this end, the shaft 148 is provided with a longitudinal groove 154 engaging with a pin 155 driven into a collar 156 which forms an integral part of the plate 58^a. The plate 58^a is held stationary 100 between a head 157 of the collar 156 at one side of the ears 158 and a hub 159 forming an integral part of said plate. In this manner, when the carriage is moved to letter-space the card, the shaft and the plate are 105 moved therewith, the rotating connection being maintained between the shaft and the stationary piece 58^a by means of the pin 155 engaging with the groove 154 in the shaft 148. 110 According to another form of this invention, the card-positioning means are modified to provide a more positive adjustment therefor. Referring to Figures 26, 27 and 28, in which this modification is illustrated, it 115 will be noted that there is provided a stop device 160 for limiting the lowermost position of the card-holding frame and a separate stop device 161 for positioning the card for the first line of typing upon the stencil-sheet. Both stop devices are pivoted upon a shoulder-stud 162, and are provided with elongated slots 163 for receiving eccentric studs 164, each having a hole 165 for receiving screws 166. The stop device 161 is 120 125 130

mounted at one side of the plate 98, and is provided with a bent tab 167 protruding through a hole 168 in the plate 98. When the handle 19 is moved rearwardly, as shown in Figure 27, to drive the sector 20 by means of an extension 169, a spring 170, which normally holds the extension 169 away from the sector, is stretched as shown in Figure 26, thereby forcing the pawl 99 out of engagement with the tab 167, to permit line-feeding of the plate after being positioned for the first line of typing upon the stencil-sheet. In order to facilitate the adjustment of the eccentric studs 164, each is provided with a nick 171 for receiving a wrench, to rotate the stud and then to permanently locate it by either driving a pin in the plate 98 or by upsetting some metal into the nick by means of a chisel.

20 The modification hereinbefore described is illustrated in connection with means for adjusting the position of the platen relatively to the printing point. To this end, there are provided a plurality of brackets 172 fast to the carriage 173 and screws 174 for approximately positioning the plates 98 upon said brackets. The screws are slightly tightened and the frames are tapped to position, whereupon screws 175 holding the brackets 25 to the carriage are loosened and the plates 98 are doweled to the brackets at 176. It will be understood that the holes 177, through which the screws 174 are passed, are considerably larger than the body part thereof, thus permitting the adjustment of the plates preparatory to their being doweled to the brackets. It will be understood that in another form of this invention the adjustable feature hereinbefore described is eliminated, and, then, the side plates 98 are directly fastened to the carriage by means of screws 182 through holes 183 in bent portions 184 of the plates 98.

As it is desirable to use a standard 45 Underwood typewriting machine, and to rebuild as little as possible for embodying the stencil device in the machine, the shaft 94 protrudes through the frame of the machine to the outside thereof, and, in order to 50 provide a bearing for the shaft at a point where the frame is cut away to clear the carriage of the machine, there is provided a plate 178 fast to the frame by means of screws 179. For the same reason specified, 55 there is provided the bracket 138 fast to the frame by means of screws 181, said bracket being provided for the purpose of carrying the stud 137 upon which the lever 136 is rockably mounted.

60 Sometimes, comparatively thin cards are used, and then, owing to the small difference in thickness between the card and the stencil-sheet, the mechanism hereinbefore described may be omitted, the type-bars being

flexible enough to take care of the difference 65 in the thickness and still deliver a clear impression of the types.

Variations may be resorted to within the scope of the invention, and portions of the improvements may be used without others. 70

Having thus described my invention, I claim:

1. In a combined typewriting and stencil-cutting machine having a revoluble platen, typing elements, and a card-holding frame 75 for receiving a stencil-card having a paper-frame and a stencil-sheet stretched across an opening therein, means controlled by the platen to line-space the card-holding frame, and latchable means controlled by the card-holding frame for vibrating a ribbon in front of the types when typing a plurality of lines upon the frame of the card and for silencing the ribbon when typing upon the stencil-sheet. 85

2. The combination with a typewriting machine having a revoluble platen and typing instrumentalities, of a stencil-device embodied in the machine, means for holding a card in front of the platen, and means latchable in operative position and controlled by the card-holding means and effective to selectively vibrate or silence a ribbon in front of the types at certain positions of the card. 90

3. The combination with a typewriting machine having a stencil-device embodied therein, of a revoluble platen, a card-carrying frame co-operating with the platen to line-space a card in front thereof, said platen having a line-spacing mechanism, and manually-operable means, independent of the line-spacing mechanism, for positioning the card, so that it will be typed upon a predetermined line, uniformly positioned 100 relatively to the top and bottom edges thereof, said means being automatically rendered ineffective upon being released, so that the card may be subsequently line-spaced by means of the line-spacing mechanism. 105

4. The combination with a typewriting machine having a stencil-device embodied therein, of a revoluble platen, a card-carrying frame co-operating with the platen to line-space a card in front thereof, said platen having a line-spacing mechanism, manually-operable means, independent of the line-spacing mechanism, for positioning the card, so that it will be typed upon a predetermined line, uniformly positioned relatively to the top and bottom edges thereof, said means being automatically rendered ineffective upon being released, to permit the card to be subsequently line-spaced by means of the line-spacing mechanism, and means controlled by the card-carrying frame for effectively vibrating a ribbon-mechanism in front of the types when the upper portion 110 115 120 125

of the card is in the printing field, and for silencing the ribbon when the lower portion of the card is being typed upon.

- of the card is in the printing field, and for silencing the ribbon when the lower portion of the card is being typed upon.

5. The combination with a typewriting machine having a stencil-device embodied therein, of a revoluble platen geared to a card-carrying frame designed to move upwardly and downwardly in an inclined path in front of the platen and adjacent thereto, a line-spacing mechanism effective to line-space the card through mechanism operatively connected to the axle of said platen, and means for quickly positioning the card to receive typing upon a predetermined line uniformly spaced from the upper and lower edges of the card, said means including a gear mechanism for revolving said platen, and a stop engaging said mechanism for arresting the movement thereof. 70

10 6. The combination with a typewriting machine having a stencil-device embodied therein, of a revoluble platen geared to a card-carrying frame designed to move upwardly and downwardly in an inclined path in front of the platen and adjacent thereto, a line-spacing mechanism effective to line-space the card through mechanism operatively connected to the axle of said platen, and means for quickly positioning the card to receive typing upon a predetermined line uniformly spaced from the upper and lower edges of the card, said means including a gear mechanism for revolving said platen, and a stop engaging said mechanism for arresting the movement thereof. 75

15 7. The combination with a typewriting machine having a stencil-device embodied therein, of a revoluble platen geared to a card-carrying frame designed to move upwardly and downwardly in an inclined path in front of the platen and adjacent thereto, a line-spacing mechanism effective to line-space the card through mechanism operatively connected to the axle of said platen, and means for quickly positioning the card to receive typing upon a predetermined line uniformly spaced from the upper and lower edges of the card, said means including a pivotally-mounted handle, gearing for operatively connecting the handle to the platen, 80

20 to rotate the same, and a stop-device including a pawl pivotally mounted on said handle and a fixed member effective to interpose the pawl when the handle is operated, thereby arresting the rotation of the platen. 85

25 8. The combination with a typewriting machine having a stencil-device embodied therein, of a revoluble platen geared to a card-carrying frame designed to move upwardly and downwardly in an inclined path in front of the platen and adjacent thereto, a line-spacing mechanism effective to line-space the card through mechanism operatively connected to the axle of said platen, and means for quickly positioning the card to receive typing upon a predetermined line uniformly spaced from the upper and lower edges of the card, said means including a pivotally-mounted handle, gearing for operatively connecting the handle to the platen, 90

30 to rotate the same, and a stop-device including a pawl pivotally mounted on said handle and a fixed member effective to interpose the pawl when the handle is operated, thereby arresting the rotation of the platen. 95

35 9. The combination with a typewriting machine having a stencil-device embodied therein, and including a carriage, a revoluble platen and typing instrumentalities, of a card-carrying frame disposed to be moved upwardly and downwardly in a straight path in front of the platen and tangent thereto, means latchable in operative position and controlled by the card-holding frame and effective to vibrate a ribbon in front of the types at predetermined positions of the card-carrying frame, and means effective upon moving said frame upwardly to a predetermined point above its lowest position to silence the ribbon in certain other positions of the card-carrying frame. 100

40 10. The combination with a typewriting machine having a stencil-device embodied therein, and including a carriage, a revoluble platen and typing instrumentalities, of a card-carrying frame disposed to be moved upwardly and downwardly in a straight path in front of the platen and tangent thereto, means controlled by the card-holding frame and effective to vibrate a ribbon in front of the types at predetermined positions of the card-carrying frame and to silence the ribbon in certain other positions of the card-carrying frame, means for line-spacing the card simultaneously with the return of the carriage, a handle carried on said carriage, means controlled by said handle for accurately positioning the card to receive the first line of typing upon the lower portion of the card, and means effective to silence the ribbon. 105

45 11. The combination with a typewriting machine having a stencil-device embodied therein, and including a carriage, a revoluble platen and typing instrumentalities, of a card-carrying frame disposed to be moved upwardly and downwardly in a straight path in front of the platen and tangent thereto, and means controlled by the card-holding frame and effective to vibrate a rib- 110

50 12. The combination with a typewriting machine having a stencil-device embodied therein, and including a carriage, a revoluble platen and typing instrumentalities, of a card-carrying frame disposed to be moved upwardly and downwardly in a straight path in front of the platen and tangent thereto, and means controlled by the card-holding frame and effective to vibrate a rib- 115

55 13. The combination with a typewriting machine having a stencil-device embodied therein, and including a carriage, a revoluble platen and typing instrumentalities, of a card-carrying frame disposed to be moved upwardly and downwardly in a straight path in front of the platen and tangent thereto, and means controlled by the card-holding frame and effective to vibrate a rib- 120

60 14. The combination with a typewriting machine having a stencil-device embodied therein, and including a carriage, a revoluble platen and typing instrumentalities, of a card-carrying frame disposed to be moved upwardly and downwardly in a straight path in front of the platen and tangent thereto, and means controlled by the card-holding frame and effective to vibrate a rib- 125

65 15. The combination with a typewriting machine having a stencil-device embodied therein, and including a carriage, a revoluble platen and typing instrumentalities, of a card-carrying frame disposed to be moved upwardly and downwardly in a straight path in front of the platen and tangent thereto, and means controlled by the card-holding frame and effective to vibrate a rib- 130

70 16. The combination with a typewriting machine having a stencil-device embodied therein, and including a carriage, a revoluble platen and typing instrumentalities, of a card-carrying frame disposed to be moved upwardly and downwardly in a straight path in front of the platen and tangent thereto, and means controlled by the card-holding frame and effective to vibrate a rib- 135

bon in front of the types at predetermined positions of the card-carrying frame and to silence the ribbon in certain other positions of the card-carrying frame, said means including a cross-bar fast to the lower portion of the carrying frame, a plate adjacent the card-carrying frame and at the rear thereof, said plate being rockably mounted on a shaft and having teeth engaging with said cross-bar, whereupon the plate will be swung to a different position, by the action of the cross-bar when the card-carrying frame is moved either upwardly or downwardly, and means controlled by said plate for engaging a ribbon-vibrating mechanism including a normally vibrating pin controlled by the typing instrumentalities.

12. The combination with a typewriting machine having a stencil-device embodied therein, and including a carriage, a revolute platen and typing instrumentalities, of a card-carrying frame disposed to be moved upwardly and downwardly in a straight path in front of the platen and tangent thereto, means controlled by the card-holding frame and effective to vibrate a ribbon in front of the types at predetermined positions of the card-carrying frame and to silence the ribbon in certain other positions of the card-carrying frame, said means including a cross-bar fast to the lower portion of the carrying frame, a plate adjacent the card-carrying frame and at the rear thereof, said plate being rockably mounted on a shaft and having teeth engaging with said cross-bar, whereupon the plate will be swung to a different position, by the action of the cross-bar when the card-carrying frame is moved either upwardly or downwardly, and means controlled by said plate for engaging a ribbon-vibrating mechanism including a normally vibrating pin controlled by the typing instrumentalities, and means for locking said plate in either of its positions to vibrate the ribbon or to positively hold it in a silenced position.

13. The combination with a typewriting machine having a stencil-device embodied therein, and including a carriage, a revolute platen and typing instrumentalities, of a card-carrying frame disposed to be moved upwardly and downwardly in a straight path in front of the platen and tangent thereto, means controlled by the card-holding frame and effective to vibrate a ribbon in front of the types at predetermined positions of the card-carrying frame and to silence the ribbon in certain other positions of the card-carrying frame, said means including a cross-bar fast to the lower portion of the carrying frame, a plate adjacent the card-carrying frame and at the rear thereof, said plate being rockably mounted on a shaft and having teeth engaging with said cross-bar, whereupon the plate will be swung to

a different position, by the action of the cross-bar when the card-carrying frame is moved either upwardly or downwardly, and means controlled by said plate for engaging a ribbon-vibrating mechanism including a normally vibrating pin controlled by the typing instrumentalities, and means for locking said plate in either of its positions to vibrate the ribbon or to positively hold it in a silenced position, said last-mentioned means including a disk fast to the shaft upon which the plate is rotatably mounted, said disk having notches therein, and a latch resiliently engaging with one of the notches, said latch being provided with a cam-finger, forming an integral part thereof, said finger being controlled by the cross-bar on the card-carrying frame in a manner to withdraw the latch from engagement with the notches of the disk previously to changing the position of the plate.

14. The combination with a typewriting machine having a carriage, a platen revolubly mounted thereon, means borne by said carriage to line-space the platen, typing instrumentalities and a universal member controlled by said typing instrumentalities, of a stencil-device embodied in the typewriting machine, the stencil-device including a card-carrying frame adjacent the platen and in front thereof, the carrying frame being arranged to be moved upwardly and downwardly by rotating the platen, means effective to vibrate a ribbon in front of the types of said typing instrumentalities when operatively connected with said universal member, and laterally stationary devices co-operating with said frame in any lateral position it may take for connecting said universal member and the vibrating means so as to cause said ribbon to be vibrated at certain upwardly-disposed positions of said frame.

15. The combination with a typewriting machine having a carriage, a platen revolubly mounted thereon, means borne by said carriage to line-space the platen, typing instrumentalities and a universal member controlled by said typing instrumentalities, of a stencil-device embodied in the typewriting machine, the stencil-device including a card-carrying frame adjacent the platen and in front thereof, the carrying frame being arranged to be moved upwardly and downwardly by rotating the platen, and means controlled by the universal member to vibrate a ribbon in front of the types of said typing instrumentalities at certain positions of the card-carrying frame, said last-mentioned means including a ribbon-vibrator in front of the card and arranged to vibrate in a path parallel thereto, a pin borne by the universal member, and means effective to throw the ribbon-vibrator into engagement with said pin at a predetermined position of the card-holding frame.

16. The combination with a typewriting machine having a carriage, a platen revolvably mounted thereon, means borne by said carriage to line-space the platen, typing instrumentalities and a universal member controlled by said typing instrumentalities, of a stencil-device embodied in the typewriting machine, the stencil-device including a card-carrying frame adjacent the platen and in front thereof, the carrying frame being arranged to be moved upwardly and downwardly by rotating the platen, and means controlled by the universal member to vibrate a ribbon in front of the types of said typing instrumentalities at certain positions of the card-carrying frame, said last-mentioned means including a ribbon-vibrator in front of the card and arranged to vibrate in a path parallel thereto, a pin borne by the universal member, and means effective to throw the ribbon-vibrator into engagement with said pin at a predetermined position of the card-holding frame, said last-mentioned means including a shaft parallel to the card and at the rear thereof, a plate fast to said shaft, a tooth in the card-carrying frame, effective to engage with a groove in said plate, thereby swinging the shaft each time that the card is either raised or lowered, said plate being provided with flat portions for locking the shaft in immovable positions after the swinging thereof, said positions being maintained by the flat portions of the plate engaging with a flat surface of the card-carrying frame, and a link operatively connecting the ribbon-vibrator to said shaft, whereby, upon swinging the shaft, the ribbon-vibrator will either be connected to or disconnected from the pin on the universal member. 70
17. The combination with a front-strike typewriting machine having a platen and typing instrumentalities including resilient type-bars, of a card-holding frame for supporting and guiding the card in a flat condition in front of the platen, said card including a comparatively thick paper-frame and a comparatively thin stencil-sheet stretched across an opening at the bottom of the card, and means controlled by the card-carrying frame to regulate the blow of the type-bars upon the paper-frame and upon the stencil-sheet. 75
18. The combination with a front-strike typewriting machine having a platen and typing instrumentalities including resilient type-bars, of a card-holding frame for supporting and guiding the card in a flat condition in front of the platen, said card including a comparatively thick paper-frame and a comparatively thin stencil-sheet stretched across an opening at the bottom of the card, and means controlled by the card-carrying frame to regulate the blow of the type-bars upon the paper-frame and upon the stencil-sheet, said means including a tapered arcuate plate slidably mounted upon the type-bar-sector of the machine, designed to increase its thickness when slid in one direction and to decrease its thickness when slid in the opposite direction. 80
19. The combination with a front-strike type-writing machine having a platen and typing instrumentalities including resilient type-bars, of a card-holding frame for supporting and guiding the card in a flat condition in front of the platen, said card including a comparatively thick paper-frame and a comparatively thin stencil-sheet stretched across an opening at the bottom of the card, and means controlled by the card-carrying frame to regulate the blow of the type-bars upon the paper-frame and upon the stencil-sheet, said means including a tapered arcuate plate slidably mounted upon the type-bar-sector of the machine, designed to increase its thickness when slid in one direction and to decrease its thickness when slid in the opposite direction, said arcuate plate being operatively connected to a rocking lever by means of a pin-and-slot arrangement, the lever being in turn connected by means of a link to a rock-shaft actuated by the card-holding frame. 85
20. In a combined typewriting and stencil-cutting machine having a platen, a card-holding frame disposed to be moved in front of the platen, said platen being positively geared to the frame, releasable means for holding a backing over a portion of the platen, said means being built within the platen, the periphery thereof having an unobstructed continuous surface, and devices mounted on the end of said platen for effecting the release of said holding means. 90
21. In a combined typewriting and stencil-cutting machine having a platen, a card-holding frame disposed to be moved in front of the platen, said platen being positively geared to the frame, means for holding a backing over a portion of the platen, said means being built within the platen, the periphery thereof having an unobstructed continuous surface, said means including a longitudinal slot parallel to the axis of the platen for receiving a bent edge of the backing, and a groove parallel to the slot for housing an eccentric rod journaled in plates at the ends of the platen, and means at one end of the platen to rotate said eccentric rod, thereby binding the other bent edge of the backing. 95
22. In a combined typewriting and stencil-cutting machine having a platen, a card-holding frame disposed to be moved in front of the platen, said platen being positively geared to the frame, means for holding a backing over a portion of the platen, said means being built within the platen, the periphery thereof having an unobstructed 100
- 105
- 110
- 115
- 120
- 125
- 130

continuous surface, said means including a longitudinal slot parallel to the axis of the platen for receiving a bent edge of the backing, and a groove parallel to the slot for housing an eccentric rod journaled in plates at the ends of the platen, and means at one end of the platen to rotate said eccentric rod, thereby binding the other bent edge of the backing, said last-mentioned means including a cam-plate engaging an arm fast to the eccentric rod at the end thereof, and a finger-piece fast to the cam-plate whereby the eccentric rod may be operated.

23. The combination with a typewriting machine having a revoluble platen, a line-spacing mechanism therefor, a carriage and typing instrumentalities, of means for presenting a stencil-card to the printing field in front of the platen, said means including a rigid card-carrying frame or pocket for receiving the card, gearing for positively connecting the frame to the periphery of the platen, a handle, and interponents including a gear system for connecting said handle to said platen, and means controlled by the card-carrying frame to automatically raise a ribbon in front of the types to cover the printing point at certain positions of the card-carrying frame, said last-mentioned means being also effective to silence the ribbon at certain positions of the card-carrying frame.

24. The combination with a typewriting machine having a revoluble platen, a line-spacing mechanism therefor, a carriage and typing instrumentalities, of means for presenting a stencil-card to the printing field in front of the platen, said means including a rigid card-carrying frame or pocket for receiving the card, and gearing for positively connecting the frame to the periphery of the platen, means controlled by the card-carrying frame to automatically raise a ribbon in front of the types to cover the printing point at certain positions of the card-carrying frame, said last-mentioned means being also effective to silence the ribbon at certain positions of the card-carrying frame, and mechanism effective to lock the means for automatically raising the ribbon either in its effective or ineffective position, said locking mechanism being also controlled by the card-carrying frame.

25. The combination with a typewriting machine having a revoluble platen and a card-carrying frame adjacent thereto and geared so that the card-carrying frame may be moved upwardly and downwardly by the rotation of the platen, and a line-spacing mechanism operatively connected to the platen and effective to line-space a card, of means operatively connected to the platen, independent of the line-spacing mechanism, effective to position the card for a predetermined line of printing, said means includ-

ing a handle and a pawl arrangement, the pawl co-operating with a fixed stop to arrest the handle, and means for disconnecting the pawl from the fixed stop upon releasing the handle.

26. The combination with a typewriting machine having a revoluble platen and a card-carrying frame adjacent thereto and geared so that the card-carrying frame may be moved upwardly and downwardly by the rotation of the platen, and a line-spacing mechanism operatively connected to the platen and effective to line-space a card, of means operatively connected to the platen, independent of the line-spacing mechanism, effective to position the card for a predetermined line of printing, said means including a handle and a pawl arrangement, the pawl co-operating with a fixed stop to arrest the handle, means for disconnecting the pawl from the fixed stop upon releasing the handle, and means controlled by the card-carrying frame and effective to vibrate a ribbon in front of the types of the machine when writing upon a certain portion of the card in the card-carrying frame, said last-mentioned means being also effective to silence the ribbon when typing upon another portion of the card.

27. In a typewriting machine, in combination, a platen, a vibratory U-shaped universal bar-member, a downwardly-extending arm on the bottom of said member, a laterally-disposed pin fixed in said arm, and a ribbon-vibrating mechanism, said mechanism including an upwardly-extending rocking arm having an open slot in its upper end for engaging around said pin, an axle for said arm arranged for movement upwardly and downwardly, a forwardly-extending arm pivoted on said axle and having a fixed relation to said slotted arm, and an upwardly-extending member pivoted on the end of said forwardly-extending arm arranged for disposing a ribbon adjacent said platen at the printing line thereof upon movement of said universal bar-member rearwardly.

28. A type-bar segment for a front strike typewriting machine, including an upright arcuate plate having a plane body-portion and a forwardly-projecting arcuate pad, said pad having its entire front surface disposed in a plane which makes a small angle with the plane of said body-portion.

29. A type-bar segment for a front strike typewriting machine, including an upright arcuate plate having a plane body-portion and a forwardly-projecting arcuate pad which has its front surface disposed in a plane which makes a small angle with the plane of said body-portion, an arcuate anvil-member mounted on said pad for movement therealong and having its rear face angularly inclined in an opposite manner from

the face of said pad, so that the front face of the anvil-member will have the same angular relation with the plane of said body-portion when the anvil-member is moved on 5 said pad, and means for holding said anvil-member on said pad in a plurality of positions.

30. A type-bar segment for a front strike typewriting machine, including an upright 10 arcuate plate having a plane body-portion and a forwardly-projecting arcuate pad, whose front surface is disposed in a plane which makes a small angle with the plane of said plate, said pad having two concentric curved slots through it and said plate integrally joined thereto in the rear, one 15 of said slots being positioned on each side of the vertical center line of said pad, an arcuate anvil-member adjustably mounted 20 on said pad and having its rear face inclined oppositely from the face of said pad and its front face arranged for having the same angular relation with said plate in a plurality of positions on said pad, and 25 means for holding said anvil-member on said pad, said means including two pins fast to said anvil-member, one being disposed for movement in each of said slots and extending rearwardly therethrough, a 30 loose collar around each of said pins disposed next to said plate, a collar fastened on the rear end of each of said pins, and a spring disposed around each of said pins between the fixed and the loose collars thereon for holding said anvil-member tightly 35 against said pad in any position the former may be moved.

31. A ribbon-vibrating mechanism for a typewriting machine, including a longitudinally-disposed shaft, a flange-like head on 40 one end of said shaft, an axle fastened to said flange eccentrically with respect to said shaft, a bushing on said axle, an upwardly-extending arm fast on said bushing and having an open slot in its upper end, a forwardly-extending arm fast on said head, and an upwardly-extending arm pivoted on 45 the end of said forwardly-extending arm and arranged for guiding a ribbon at typing position in said machine upon movement of said slotted arm rearwardly.

32. In a typewriting machine, the combination with a platen, a universal bar-member, a ribbon-vibrator-mechanism and a 50 card-carrying frame movable upwardly and downwardly in front of said platen, of mechanism for operatively connecting said member and said vibrator-mechanism including a laterally-disposed pin in said member, and an upwardly-extending arm of said vibrator-mechanism having an open slot in its upper end normally below said pin, said arm being arranged for movement upwardly and downwardly upon predeter-

mined movements of said frame to engage 55 said slot around said pin.

33. In a typewriting machine having a carriage, a revoluble platen and typing instrumentalities, the combination with a normally silent ribbon-vibrator, a universal-bar-member arranged for vibration upon operation of each of said typing instrumentalities, and a frame movable upwardly and downwardly in front of said platen and adjacent thereto for carrying a stencil-card, 70 having an upper frame-portion and a lower stencil-sheet portion, of means for maintaining said universal bar-member and said ribbon-vibrator in operative engagement for actuating the latter while data is typed 75 on said stencil-card frame-portion, means for silencing said ribbon-vibrator while said stencil-sheet is at the printing line, and instrumentalities carried by said carriage for adjusting said engagement-maintaining 80 means.

34. In a typewriting machine having a revoluble platen and typing instrumentalities, the combination with a normally silent 90 ribbon-vibrator, a universal bar-member vibrated upon operation of said instrumentalities, and a frame movable upwardly and downwardly in front of said platen and adjacent thereto for carrying a stencil-card consisting of an upper frame-portion long 95 enough for having printed thereon several lines of data and a lower stencil-sheet, of means for bringing said universal bar-member and said vibrator into operative engagement to actuate the latter, and means 100 including a cam-controlled latch actuated by said frame for maintaining said operative engagement while two or more lines of data are typed on the upper frame-portion of said card.

35. In a typewriting machine having a revoluble platen, in combination, a vibratory universal bar-member, a ribbon-vibrator, and mechanism for operatively connecting and disconnecting said member and vibrator, 110 said mechanism including an arm on said member, a laterally-disposed pin in said arm, a laterally-disposed shaft below said pin, an arm on said shaft, an annular flange-like head on said shaft, a lateral member fastened to said head eccentrically of said shaft on the same side as said last-named arm, a bushing on said lateral member arranged for rotation thereon, an upwardly-extending arm fast on said bushing and arranged with an open slot in its upper end in close proximity below said lateral pin, a forwardly-extending arm fixed on said bushing for pivotally supporting said vibrator on its outer end, and means actuated upon revolving said platen for raising and lowering the 115 end of said first-named arm, whereby said slot may be engaged and disengaged re- 120 125

spectively with said lateral pin in said vibratory member.

36. In a device of the class described, in combination, a platen-shaft, a card-carrying frame movable upwardly and downwardly in front of said platen and adjacent thereto, and means for moving said frame from a lower position upwardly to a predetermined point relative to said platen, said means including a rack on said frame, a gear-wheel on said platen-shaft meshing with said rack, a pinion on said platen-shaft, a pivoted sector having an internal gear that meshes with said pinion, a handle for pushing said sector counterclockwise, a stop positioned for arresting the revolution of said handle when said frame is moved to the predetermined point, and devices preventing movement of said sector past said handle when the movement of the latter is arrested.

37. In a typewriting machine, in combination, a carriage, a pair of mounting plates supported on said carriage, a platen-shaft extending through said plates and journaled in the ends of said carriage, a platen on said shaft between said plates, a card-carrying frame movable upwardly and downwardly between said mounting plates in front of said platen and adjacent thereto, and means for stopping said frame at a plurality of predetermined points relative to said platen, said means including a rack adjacent each side edge of said frame, two gears, one at each side of said platen engaging said racks, a pinion on said platen-shaft adjacent the outer frame of the right-hand one of said mounting plates, a sector-plate revolvably mounted on said right-hand mounting plate and arranged with an internal gear which meshes with said pinion, and a stop-plate adjustably mounted on the inner face of said right-hand mounting plate and having a lug-member arranged to project through an oversize hole in said right-hand mounting plate for arresting said sector-plate in a plurality of positions, whereby said frame which is connected with said sector-plate through unyielding gear-interponents may be stopped in a plurality of positions.

38. In a typewriting machine, the combination with a carriage, a platen, a platen-shaft and a stencil-card carrying frame movable up and down in front of said platen and adjacent thereto, of means for moving, at one operation, said frame downwardly from its starting position to a certain predetermined point for typing a line of characters on the upper portion of a stencil-card and afterwards moving said frame upwardly at one operation a predetermined amount for thereafter typing a plurality of lines of characters on the lower portion of the card, said means including racks on said frame, gears on said platen-shaft engaging said racks, a pinion on said shaft, a sector having

an internal gear arranged for meshing with said pinion, a handle pivoted concentrically with said sector, a pivoted member on said handle arranged for pushing said sector clockwise, a spring urging said member counterclockwise, a lug on said handle for pushing said sector counterclockwise, a spring stronger than said first-named spring for urging said handle clockwise, a heel on said pivoted member arranged for engagement with said sector upon movement of said handle clockwise to swing said pivoted member clockwise, a stop for engaging said sector and arresting its clockwise movement, and a stop positioned for engaging said pivoted member during the counterclockwise movement of said sector under action of said handle, said pivoted member being disengaged from said stop by action of said stronger spring forcing said handle clockwise to bring said heel against said sector and swinging said pivoted member clockwise.

39. In a device of the class described, in combination, an upright mounting plate, a rotatable plate having the form of a sector of a circle slightly less than 180° in arc, pivoted on said mounting plate and having an internal gear, a handle pivoted on said mounting plate co-axially with said sector and disposed outside of the latter, a platen arranged for being driven by said rotatable plate, an arm-member of said handle extending beyond the pivot thereof, a lug on said handle for engaging against the outer edge of said sector between its pivot and its curved periphery for pushing said sector counterclockwise, a pawl-member pivoted on said handle on the opposite side of the latter from said lug and more than 180° from the latter and having a rear rim portion about its pivot arranged for engaging said sector to push it clockwise, a stop for engaging the forward end of said pawl upon movement of said handle clockwise, a spring arranged for urging said pawl counterclockwise, a heel on said pawl adjacent its pivot arranged for engaging said sector when the latter is being pushed by said lug so as to arrest the motion of the sector upon engagement of said pawl and said stop, and a spring stronger than said first-named spring arranged for urging said handle clockwise and normally holding said heel in engagement with said sector so as to swing the forward end of said pawl normally free of said stop, and permit counterclockwise movement of said platen independent of said handle.

40. A handle for operating a stencil-card feeding mechanism of the class described, including an upright lever having one end arranged to be conveniently grasped by an operative, a transversely-bent pushing lug on the opposite end of the lever, a pivot for said handle adjacent said lug, a pawl pivoted

- on said handle intermediate said pivot and said first-named end, said pawl having a rear pushing portion around its pivot, a forward toe-portion and a heel-portion disposed adjacent to the pivot of said pawl and extending inwardly toward the pivot of said handle, a spring arranged for urging said pawl counterclockwise, and a spring stronger than said first-named spring for urging said lever clockwise. 41. A platen-rotating mechanism of the class described, including a mounting plate, a platen-shaft extending through said mounting plate, a handle pivoted on said plate a short distance from said shaft, a sector mounted co-axially with said handle and having an internal gear, a pinion on said platen-shaft meshing with said sector-gear, a fixed member on said handle for driving said sector in one direction, and a pivoted member mounted on said handle and having a rim-portion around its pivot disposed for engaging said sector to drive it in the opposite direction, a non-releasable stop for arresting the motion of said sector when driven by said pivoted member, and a releasable stop means including said pivoted member for temporarily stopping said sector and said platen when driven by said fixed member. 42. In a device of the class described, in combination, a line-spacing mechanism, a platen, a platen-shaft, a pinion on said shaft, a pivoted sector having an internal gear meshing with said pinion, a handle mounted co-axially with said sector, a pawl pivoted on said handle and having a front toe-portion, instrumentalities for moving said sector counterclockwise with said handle, means for engaging the toe of said pawl to arrest the counterclockwise motion of said handle, a spring arranged for urging said pawl counterclockwise, and a heel on said pawl held by said spring in engagement with said sector as the latter is rotated counterclockwise upon operation of said line-spacing mechanism, the engagement of said sector and said heel being effective for swinging said toe of said pawl clockwise sufficiently to clear said arresting means, whereby said platen may be line-spaced in a counterclockwise direction past the limit of its counterclockwise movement under action of said handle. 43. In a device of the class described, in combination, a platen, a platen-shaft, a pinion on said shaft, a pivoted sector having an internal gear arranged for meshing with said pinion, a handle for an operative of said device mounted co-axially with said sector and having a portion extending beyond its axis, a lug on said extended portion for engaging said sector to revolve it about its axis, a pawl pivoted on said handle, a spring arranged for urging said pawl counterclockwise, a heel on said pawl disposed for engaging said sector so as to limit the counterclockwise movement of said pawl by said spring, said heel and said lug having a lost-motion relation to said sector so that when the latter is engaged by said lug said pawl is free to be swung by said spring to the extreme limit of its counterclockwise movement, a stop arranged for engaging the forward end of said pawl and arresting the counterclockwise movement of said handle, and a spring on said handle stronger than said pawl-spring for urging the handle, after it is released by the operative, in a clockwise direction against the co-action of said pawl-spring, said heel and said sector, the last-named movement of said handle swinging said pawl clear of said stop to permit further counterclockwise movement of said platen by rotation of said platen-shaft independent of said handle. 44. In a device of the class described, in combination, a carriage, a pair of mounting plates on said carriage, a platen-shaft extending through said mounting plates to be journaled in said carriage, a pinion on said shaft, a sector pivoted on the right-hand one of said mounting plates and arranged with an internal gear, which meshes with said pinion, a handle mounted on said right-hand mounting plate co-axially with said sector, instrumentalities carried by said handle for engaging said sector to rotate it clockwise, instrumentalities on said handle for engaging said sector to rotate it counterclockwise, a stop-plate on said right-hand mounting plate arranged for movement about the axis of said handle, a lug on said stop-plate extending outwardly through an oversized hole in said right-hand mounting plate for engaging said sector to arrest the clockwise rotation thereof, a second stop-plate on said right-hand mounting plate arranged for movement about the axis of said handle, a lug on said second stop-plate extending through a second oversized hole in said mounting plate for engaging with said first-named instrumentalities on said handle to arrest the counterclockwise movement of the latter, and means for adjustably locating plate for binding the stop-plates to through arcuate slots in each of said stop-plates disposed about its axis, said screws being threaded into said right-hand mounting plates for binding the stop-plates to said mounting plate in varying positions. 45. In a typewriting machine, the combination with a platen against which may be fed a work-piece having transverse sections of different thicknesses by revolving the platen, and resilient type-bars striking against the work-piece at the printing line of said platen, of an anvil arranged to be struck by said type-bars just before the latter strike the work-piece, and means operated upon revolving said platen for varying

the thickness of said anvil, whereby the position of the face of the anvil relative to the surface of the platen at the printing line may be automatically adjusted to the different sections of said work-piece movable by revolving said platen.

46. In a typewriting machine, the combination with a rotatable platen and a stencil-card frame movable upwardly and downwardly in front of said platen upon rotation thereof, of a vibratory universal bar-member, a ribbon-vibrating mechanism arranged for engaging said universal bar-member upon being moved upwardly a short distance, and instrumentalities for operatively connecting and disconnecting said member and said ribbon-vibrating mechanism and maintaining them in their connected or disconnected relation during the typing of a plurality of lines in said machine, said instrumentalities including a laterally-disposed shaft below said platen, a flange-like plate fast on said shaft, a downwardly-extending link-member pivotally fastened to said plate in the rear of said shaft and having its lower end engaging said ribbon-vibrating mechanism, a downwardly-depending tooth on said plate and forming with the latter substantial V-shaped notches on each side of said tooth, a spring-pressed roller engaging in one of said notches for holding said shaft against accidental rotation, the outer end of said tooth being shaped to permit it to cam said roller aside when pressed firmly against the latter so that the roller may engage in the other V-shaped notch, and devices actuated by a predetermined downward movement of said card-frame for rotating said shaft clockwise and raising said link-member, thereby causing said vibrating mechanism to rise and engage said universal bar-member, said devices being further arranged for actuation on a subsequent predetermined upward movement of said card-frame to rotate said shaft counterclockwise, lower said link-member and disengage said vibrating mechanism from said universal bar-member.

47. In a typewriting machine, in combination, a vibratory universal bar-member, a round, laterally-disposed pin carried by said member, a ribbon-vibrating mechanism including a laterally-disposed shaft, a forwardly-extending member fast on said shaft, a flange-like head fast on said shaft, a laterally-disposed axle-member fast to said head and disposed forwardly from the center of said shaft, a bushing free to revolve on said axle-member, a forwardly-extending arm fast on said bushing, an upwardly-extending ribbon-vibrator-member pivoted adjacent the forward end of said forwardly-extending arm, a support for said forwardly-extending arm for holding it in normal, inoperative position, an upwardly-extending arm

fast on said bushing and having an open slot in its upper end disposed a short distance directly below said pin, and means for raising said forwardly-extending member and said bushing and said slotted arm upwardly a distance to cause said slotted arm to be rotated slightly clockwise by the weight of said forwardly-extending arm so as to bring the rear side of said slot into engagement with the rear side of said pin in such a way as to cam said forwardly-extending arm a small amount counterclockwise to raise it to starting position clear of said support, said slot thereafter being moved farther upwardly by said means into full operative engagement with said pin.

48. In a typewriting machine having a revolvable platen against which may be fed a work-piece having sections of variable thicknesses, the combination with resilient typing instrumentalities for striking against said platen, of an arcuate anvil positioned for being struck by said instrumentalities just before they strike said work-piece on said platen, said anvil including a curved, fixed inner member and an outer member arranged for circumferential movement on said fixed member, the adjoining faces of said members being angularly inclined so that the position of the work-face of the outer member relative to the printing line of said platen may be varied upon movement of the outer member, a laterally-disposed shaft below said platen, interponents connecting said platen and said shaft effective to rotate the latter when one of said thicknesses of the card-sections is fed away from the printing line of said platen and another section of different thickness is moved to said printing line, and interponents connecting said shaft and said movably free anvil-member arranged for sliding the latter circumferentially on said fixed anvil-member, to vary the relation of the work-face of the anvil to said platen in accordance with the rotation of said shaft and the positioning of said work-piece sections adjacent the platen.

49. In a typewriting machine having a revolvable platen against which may be fed a work-piece having sections of variable thicknesses, the combination with typing instrumentalities for striking them against said platen, of an arcuate anvil positioned for being struck by said instrumentalities just before they strike said work-piece on said platen, said anvil including a fixed inner member and an outer member arranged for circumferential movement on said fixed member, the adjoining faces of said members being angularly inclined so that the position of the work-face of the outer member relative to the printing line of said platen may be varied upon movement of the outer member, a laterally-disposed

shaft below said platen, interponents connecting said platen and said shaft effective to rotate the latter when one of said thicknesses of the card-sections is fed away from the printing line of said platen and another section of different thickness is moved to said printing line, and interponents connecting said shaft and said movable anvil-member arranged for sliding the latter circumferentially on said fixed anvil-member, said last-named interponents including an arm on said shaft, a pin in said movable anvil-member, a lever having a slot in one end for engaging said pin, and a link connecting the other end of said lever with the outer end of said arm.

50. In a typewriting machine, the combination with a platen, a card-carrying frame movable upwardly and downwardly in front of said platen and adjacent thereto for presenting to said platen a stencil-card having a thick body-portion and a thin stencil-sheet portion, a universal bar-member, and a ribbon-vibrator normally silent, 25 of a laterally-disposed shaft below said platen, means for rotating said shaft controlled by the movement of said card-carrying frame, an anvil having its outer face arranged for being adjusted relative 30 to the printing line of said platen, a mechanism actuated by rotation of said shaft for operatively connecting said universal bar-member and said ribbon-vibrator for actuat-

ing the latter, and mechanism actuated upon rotation of said shaft for adjusting the outer 35 face of said anvil, whereby it may co-operate with the position of said card-carrying frame.

51. In a typewriting machine, in combination, a platen, means for holding a back- 40 ing over a portion of said platen, said means being built within the platen so that the periphery thereof may have a substantially unobstructed, continuous surface, a handle pivoted on an end of said platen, 45 and devices controlled by said handle and mounted on the end of said platen for actuating said holding means.

52. In a device of the class described, a mounting plate, a platen-shaft passing 50 through an aperture in said plate, a platen on said shaft, a handle pivoted on said plate, gear interponents actuated by said handle for rotating said platen forwardly and backwardly, two lug-stops pivoted on said 55 mounting plate, one of said stops being disposed for arresting the counterclockwise movement of said handle, and the other of said stops being disposed for arresting the clockwise movement of said interponents, 60 said stops having slots therethrough, and eccentrically-mounted studs disposed in said slots and fastened to said plate for adjustably positioning said lug-stops.

ALFRED G. F. KUROWSKI.
